UNITED STATES PATENT OFFICE.

MORRIS STETTNER, OF BROOKLYN, NEW YORK.

DESIGN FOR A RADIOCABINET OR SIMILAR ARTICLE.

Application filed May 25, 1928. Serial No. 26,858. Term of patent 3½ years.

To all whom it may concern:

Be it known that I, MORRIS STETTNER, a citizen of the United States, residing at Brooklyn, New York city, in the county of Kings and State of New York, have invented a new, original, and ornamental Design for a Radiccabinet or Similar Article, of which the following is a specification, reference being had to the accompanying drawing, forming a part thereof.

The figure is a perspective view of a radio-cabinet showing my new design.

I claim:

The ornamental design for a radiocabinet or similar article, as shown.

In testimony whereof I affix my signature.

MORRIS STETTNER.
